US00D631901S

(12) **United States Design Patent**
Brooks et al.

(10) **Patent No.:** US D631,901 S
(45) **Date of Patent:** ** Feb. 1, 2011

(54) **PORTABLE APPARATUS FOR
DETERMINING LEAKS IN AIR DUCTS**

(75) Inventors: **Patrick J. Brooks**, Columbus, OH (US);
Shawn Michael Fortner, Massillon, OH (US); **Andrew N. Czerpak**, Erie, PA (US)

(73) Assignee: **United McGill Corporation C**,
Groveport, OH (US)

(**) Term: **14 Years**

(21) Appl. No.: **29/354,454**

(22) Filed: **Jan. 25, 2010**

(51) **LOC (9) Cl.** 15-99

(52) **U.S. Cl.** D15/199

(57) **CLAIM**

The ornamental design for a portable apparatus for determining leaks in air ducts, as shown and described.

DESCRIPTION

FIG. 1 is an isometric view of the portable apparatus for determining leaks in air ducts looking downwardly on the top and front thereof;

FIG. 2 is an isometric view of the portable apparatus for determining leaks in air ducts looking downwardly on the top and rear thereof;

FIG. 3 is an isometric view of the portable apparatus for determining leaks in air ducts looking upwardly on the bottom and rear thereof;

FIG. 4 is a front view of the portable apparatus for determining leaks in air ducts;

FIG. 5 is a top view of the portable apparatus for determining leaks in air ducts;

FIG. 6 is a bottom view of the portable apparatus for determining leaks in air ducts;

FIG. 7 is a side view of one side of the portable apparatus for determining leaks in air ducts;

FIG. 8 is a side view of the other side portable apparatus for determining leaks in air ducts; and,

FIG. 9 is a rear view of the portable apparatus for determining leaks in air ducts.

The broken lines in the drawings depict unclaimed environmental subject matter.
